UNITED STATES PATENT OFFICE.

ETHEL D. PARROTT, OF LOS ANGELES, CALIFORNIA.

EXTENSION-TABLE.

1,327,878.

Specification of Letters Patent. Patented Jan. 13, 1920.

Application filed July 21, 1919. Serial No. 312,246.

To all whom it may concern:

Be it known that I, ETHEL D. PARROTT, a citizen of the United States, residing at Los Angeles, in the county of Los Angeles and State of California, have invented a new and useful Extension-Table, of which the following is a specification.

My invention relates to extension tables and has more particular relation to the type 10 of tables in which the extension leaves are permanently assembled in the table structure and are housed beneath the main table leaves when not in use.

The object of this invention is to provide 15 a table of the above described type having hinged extension leaves medially supported by a strut member.

Another object is to provide a table having medially hinged extension leaves, all of 20 the table leaves having intermeshing alining devices and the extension leaves, in use, having a three-point support upon the table frame relieving the alining devices of shearing strains.

25 A further object is to provide a table having sectional extension leaves joined together by a blind-hinge device providing a smooth unbroken table surface.

Another object is to provide a table having 30 a hinged sectional extension leaf structure combined with a supporting strut member adjacent its hinge, the leaf sections, when in use, engaging the table frame at points relatively remote from the hinge providing a three-point support for the leaves 35 and rendering them noncollapsible by downward pressure or weight.

With these and incidental objects in view the invention consists of certain novel features of construction and combination of 40 parts, the essential elements of which are set forth in the appended claims and a preferred form of embodiment of which is hereinafter described with reference to the drawings 45 which accompany and form part of this specification.

In the drawings—

Figure 1 is a perspective view of the table extended.

50 Fig. 2 is a bottom plan view, with the pedestal removed and the extension leaves folded.

Fig. 3 is a section on line x^3-x^3 , Fig. 1.

55 Fig. 4 is a similar section showing the extension leaves folded.

Fig. 5 is a section on line x^5-x^5 , Fig. 2.

Fig. 6 is a similar section showing the first step in the unfolding of an extension leaf.

Fig. 7 is a similar view showing the leaf in final unfolded position. 60

Fig. 8 is an enlarged detail section through the blind-hinge device.

Fig. 9 is a similar detail section showing the sectional leaf in unfolded position. 65

The table embodying the present invention includes a rigid frame supported upon legs or upon a single pedestal as shown, said frame slidably supporting the main leaves of the table beneath which the extension leaves are housed when not in use. 70

The frame comprises a pair of parallel side rails 1, 2 and connected end rails 3, 4, the frame being supported upon the pedestal 5 secured to a base plate 6 extended across the frame and connected to the side rails. 75 The vertical sides of the side rails 1, 2 are provided with longitudinal grooves 7, 8. The main leaf 9 of the table has secured to its under surface, a pair of parallel slides 11, 11 which engage into the grooves 7 of the side rails and the main leaf 10 has a similar pair of slides 12, 12 engaging into the grooves 8 of the side rails. This permits an independent sliding of either of the main leaves relative to the frame. A rod 13 is 80 mounted at its ends in the end rails 3, 4 of the frame and extends longitudinally in a plane beneath the main leaves of the table and parallel with the side rails 1, 2. This rod supports the inner hinged ends of the 85 extension leaf sections in both folded and extended positions. 90

Each of the extension leaves comprise two sections 14, 15 hinged together by a blind-hinge device 16, the section 14 being connected by a hinge 17 to one end of a strut member 18 slidably journaled on the rod 13. The hinge end of the strut members has an angled surface 19 which, when the leaf is in unfolded position, is in a horizontal plane, forming an abutment support for the inner edge of the section 14 as shown in Fig. 6 and limiting the hinge movement of said section relative to the strut member. 95

The opposite end of the section 14 engages 100 upon the upper surface of the side rail 1, this arrangement providing a non-collapsing structure. The section 15 engages the upper surface of the side rail 2 of the frame and the surface 19 of the strut member extends beneath the inner edge of said section forming 110 an abutment support therefor, relieving

the hinge device 16 of downward strain. A leaf supporting bar 20, rigid on the frame, supports the outer ends of the leaf section when in folded position. (See Fig. 5.)

5 The main leaves and the sectional extension leaves are provided with the usual intermeshing dowel pins and sockets for the purpose of providing a true alinement of the several sections to present a smooth table 10 surface.

In the operation of extending the table, the main leaves are separated to expose the folded sectional leaves. The sectional leaves are then bodily lifted, the strut member 18 15 swinging about its pivot rod 13 and the section 14 of the leaf pivoting on the hinge 17, the parts assuming the position shown in Fig. 6. The leaf section 15 is then swung upwardly about the hinge 16 to the position 20 shown in Fig. 7.

After the extension leaves are positioned upon the frame rails the main leaf sections are brought together, each leaf section abutting the adjacent section with the intermeshing dowel pins and sockets engaging to align 25 the leaves.

I claim:

1. An extension table comprising a frame,

main leaves slidable thereon, a sectional extension leaf hingedly united, and a strut member slidably journaled on the frame in a direction lengthwise of the table for edge-wise adjustment of said leaf and hinged to one of the extension leaf sections. 30

2. An extension table comprising a frame, 35 main leaves slidable thereon, a pivoted strut member slidable on the frame lengthwise of the table and having its end formed as an abutment for engaging the inner edges of both leaf sections and a hinge connecting 40 the strut member and extension leaf.

3. An extension table comprising a frame, 45 main leaves slidable thereon, an extension leaf comprising two hingedly united sections, and a pivoted strut member slidable on the frame lengthwise of the table and hingedly connected to one of said leaf sections, limiting its movement and having its inner end formed to provide a supporting abutment for both leaf sections. 50

Signed at Los Angeles, California, this 14th day of July, 1919.

ETHEL D. PARROTT.
